UNITED STATES PATENT OFFICE.

WILLIAM E. HARRIS, OF SCOTTSBORO, ALABAMA, ASSIGNOR OF ONE-HALF TO C. L. JARRETT, OF SPRINGFIELD, MISSOURI.

CAR-DOOR-OPERATING MECHANISM.

1,155,922.

Specification of Letters Patent.

Patented Oct. 5, 1915.

Application filed March 22, 1915. Serial No. 16,131.

To all whom it may concern:

Be it known that I, WILLIAM E. HARRIS, a citizen of the United States, and a resident of Scottsboro, in the county of Jackson and State of Alabama, have made certain new and useful Improvements in Car-Door-Operating Mechanism, of which the following is a specification.

My invention is an improvement in car door operating mechanism, and has for its object to provide mechanism of the character specified especially adapted to operate that type of door which moves over and away from over the door opening by gravity, the said door being mounted on a track bar which is pivoted to the car at the door opening and the present invention provides an improved form of operating mechanism for swinging the track bar.

20 In the drawings:—Figure 1 is a side view of a car provided with my improved door operating mechanism and showing the door closed, Fig. 2 is a similar view showing the door open, Fig. 3 is an enlarged section 26 on the line 3—3 of Fig. 1, Fig. 4 is an enlarged section through the track bar, showing its connection with the door, and Fig. 5 is a section on the line 5—5 of Fig. 4.

The improved mechanism is shown in connection with a car 1 having a door opening 2 and a door 3 is provided for closing the opening. The door has its upper end inclined, the door being of greater height at one side than at the other side for a purpose 25 to be presently described and the door closes and opens against stops 4 and 5, the said stops being in the present instance bars secured to the car at opposite sides of the door opening. The bar 4 is at one side of the 40 door opening and near the said side and the door 3 closes against the bar when it is over the door opening.

The bar 5 is spaced apart from the door opening and the door closes against the said 45 bar when it is open. Journal pin supporting brackets are connected with the top of the door, each of the said brackets comprising a body 6 having at its lower end a substantially U-shaped engaging member comprising a body 7 integral with the brackets and depending arms 8 and 9 which are adapted to engage opposite sides of the door and are secured to the door by means of screw bolts 10.

55 It will be noted that the arm 8 is counter-

sunk in the door, while the arm 9 fits outside of the door and the screw bolts are engaged by nuts 11 at the outer face of the arm 9. The body of the bracket is somewhat nearer the arm 9 than the arm 8 and a journal pin 12 is arranged transversely of the body at the center thereof, and grooved wheels 13 are arranged on the journal pins on opposite sides of the body, each wheel being held in place by a cotter pin 14 passing through an opening in the journal pin. The wheels are spaced above the body 7 of the bracket, and the said wheels are adapted to engage ribs 15 in a track bar.

The track bar consists of a body or casting 16 of tubular construction, and of rectangular cross section, the said track bar having a split extending longitudinally of the under side thereof, and each side of the split is provided with an integral upstanding rib or rail 15. The body 6 of the bracket extends through the split and the wheels 13 engage the opposite ribs running upon the ribs and supporting the door in this manner. At its center the track bar is provided on 80 its upper side with a transverse bearing bracket 16, and a reinforcing rib 17 extends longitudinally of the bar in each direction from the bracket each of the ribs gradually decreasing in height from the bearing toward the end of the track bar. The track bar is supported by a pin 18. The pin 18 is passed through an opening in the side wall of the car, the head of the pin being inside of the car, and the outer end of the 85 pin engages a bearing 19 in one of the arms of an angle bracket 20.

The angle bracket has one arm vertical and the other horizontal, the bearing 19 being in the vertical arm, and the horizontal 95 arm has a threaded stem 21, which extends through the side of the car and is engaged by a nut 22 inside the car. A shoulder is provided between the stem and the body of the angle bracket, and the shoulder engages 100 the outer face of the car to limit the inward movement of the pin. A cotter pin 23 is provided for locking the nut 22 in place. The nut is provided preferably with diametrical openings at right angles to each 105 other and the threaded stem 21 is provided with a longitudinal slot adapted to register with the openings in the nut, and the cotter pin may be passed through the registering openings of the nut and the threaded stem. 110

Preferably the head of the pin 18 is covered by a covering block 24 of wood or the like the said block being secured to the car by means of screws 25 and the pin is arranged as hereinafter described:

- 5 The supporting pin 18 for the track bar is arranged at the opposite side of the door opening from the stop 4, and the ends of the track bar extend beyond the stops 4 and 5.
- 10 The stops 4 and 5 are of sufficient width to extend flush with the outer surface of the track bar or a little beyond the same and straps or plates 26 are arranged over the ends of the track bar to prevent any outward swinging of the said ends away from the car. Each strap is connected at its lower end to the adjacent stop 4 or 5 as the case may be and the upper end of each strap is connected with a block 27 of the same thickness as the stop. Thus the straps 26 are arranged outside of the track bar and the ends of the bar swing behind the strap.

The operating mechanism for the door or track bar is arranged at opposite ends of the track bar, means being provided at one end for opening and closing the door, and means being provided at the other end for closing the door. The means for opening and closing the door is arranged on the opposite side 25 of the stop 5 from the door opening, while the means for closing the door alone is arranged on the opposite side of the stop 4 from the door opening. The first named means comprises a lever 28, pivoted intermediate its ends as indicated at 29 to the side of the car and that end of the lever adjacent to the track bar is provided with a longitudinally extending slot 30. The track bar is provided at the said end with a pair of depending lugs 31 and a pin 32 is passed through registering openings in the lugs and through the slot 30 of the lever to pivotally connect the track bar to the lever.

45 Flexible members 33 and 34 are connected with the respective ends of the lever, the said members being chains in the present instance and the chain 34 is connected to that end of the lever having the slot 30. Each chain is provided at its lower end with 50 a ring or handle 35 and each chain passes near its lower end through a guide and keeper 36, each guide and keeper consisting of a body and ends offset laterally from the body and secured to the car to space the 55 body away from the car and the flexible member passes between the body and the car. It will be evident that when the chain 34 is pulled downwardly with the parts in the position of Fig. 1, the lever will be 60 sprung in a direction to depress that end of the track bar adjacent to the stop 5 and the door will roll of its own weight away from over the door opening, that is, into the position shown in Fig. 2. With the parts in 65 this position when the chain 33 is pulled

downward, the adjacent end of the track bar will be lifted and the door will roll over the door opening, running on the wheels 13.

The closing mechanism at the opposite side of the door consists of a flexible member 37, a chain in the present instance, connected to an eye 38 on the adjacent end of the track bar, and having at its lower end a ring or handle 39. A keeper 40 is provided for the flexible member similar to the 70 keepers 36, and it will be evident that the parts in the position of Fig. 2 the door may be closed by pulling down on the chain 37. Means is provided adjacent to each of the chains for temporarily holding the chain in 80 downward position, until the door has moved. After the door has moved into either the position shown in Fig. 1, or that shown in Fig. 2, the track bar will be held in such position by the weight of the door. 85 This temporary holding mechanism is in the form of a block or bracket 41 secured to the car below the adjacent keeper and having a pair of pins 42 extending toward the adjacent chain, and adapted to engage opposite sides of a link of the chain to hold the chain from upward movement. 90

It will be noticed that the stop 5 inclines away from the door opening toward its upper end. Because of the inclined position of 95 the track bar when the door is closed, one side of the door is made of greater length than the other so that when the door is over the door opening the opposite sides thereof will be perpendicular regardless of the inclined position of the track bar. 100

The stop 5 is inclined to be parallel with the adjacent side of the door when the door is open. A keeper 43 is provided for the bottom of the door, the said keeper being at 105 that side of the door adjacent to the stop 5 and in such position that it will engage the bottom of the door whether the door is open or closed. This keeper prevents the bottom of the door from swinging outward. Each 110 stop 4 and 5 is braced by an angle bracket 44 near each end, each of the said brackets consisting of a portion secured to the side of the car and a portion offset outwardly to engage the outer face of the stop and secured to the 115 said outer face, and extending beyond the edge of the straps so as to form keepers for the door.

A hasp 45 is hinged to the door by means of a leaf 46 which is secured to the door and 120 hinged to the hasp, and the hasp cooperates with a staple 47 on the strap 4 to hold the door closed. A pin 48 is provided for engaging the staple after the hasp is in place to prevent disengagement of the staple and the 125 pin is supported by a chain 49 connected with the strap 4. It will be noted that the pivot pin 29 which supports the lever 28 extends laterally from an X-shaped plate 50, which is secured to the inner face of the car 130

wall by means of bolts 51 which pass through the ends of the plate and through the car wall. The pin 29 is a species of hub or journal pin extending from the X-shaped plate through a suitable opening in the car wall and the lever is held in place on the pin by means of a cotter pin. A guard 52 is provided for the outer end of the lever 28 to limit the swinging movement of the lever 10 to guide the lever in its movement. It will be noted that the lever 28 adjacent to the slide 30 is offset outwardly to permit its connection with the lug 31.

I claim:

15 In a means for swinging and locking an oscillating door track for a sliding door, the combination with a track pivoted intermediately

20 ate its length of a lever pivoted adjacent to one end thereof intermediate the ends of the lever and having a slideable and pivotal connection with the track adjacent to one end of the lever, a chain connected with each end of the lever and depending therefrom, a chain connected with the opposite end of the track and depending therefrom, and means 25 in connection with the last-named chain and with the outermost of the first-named chains for engagement by the chain to prevent the chains from upward movement.

WILLIAM E. HARRIS.
